UNITED STATES PATENT OFFICE.

WILLIAM E. RICE, OF BOLIVAR, MISSOURI.

ADJUSTMENTS FOR CHIROPRACTIC TABLES.

1,360,580.

Specification of Letters Patent. Patented Nov. 30, 1920.

Application filed July 2, 1919, Serial No. 308,082. Renewed June 25, 1920. Serial No. 391,838.

To all whom it may concern:

Be it known that I, WILLIAM E. RICE, a citizen of the United States; residing at Bolivar, in the county of Polk and the State of Missouri, have invented certain new and useful Improvements in Adjustments for Chiropractic Tables, of which the following is a specification.

This invention relates to means for adjusting the tension of a lifting or supporting spring for tables of the type mentioned, being an improvement on the form of adjustment shown in my application filed November 2, 1917, Serial No. 199,908, the device as herein shown and described automatically adjusting the spring tension to the weight of the patient standing on the foot rest.

The invention consists of the novel features of construction hereinafter described, pointed out in the claims and shown in the accompanying drawings, in which:

Figure 1 is a side elevation parts being shown in section.

Fig. 2 is a front end elevation, the table being broken off.

Fig. 3 is a plan view of a U-bar.

In these drawings 1 designates the support for the table, usually referred to as the "stand" and 2 the side arms of the table, 30 only the foot portions being shown. A slightly curved casting 3 is pivotally mounted midway its ends within the stand 1, the casting being longitudinally slotted and its forward ends being formed with notches 4.

35 A bar 5 connects the arms 2 and end portions of lifting springs 6 engage said bar, said springs being coiled about a bar 6^a which also forms a pivot for the arms 2. A U-shaped bar 7 carries transverse bolts 8 and 40 9 adjacent its ends, and the bolt 9 is engaged by the remaining end portions of the springs 6. A comparatively weak spring 10 is fixed to a suitable base at the lower end and its upper end is adjustably connected to the bar 7.

The bolt 8 works in the slot of the curved casting 3 and is adapted to engage the notches 4, thereby locking the bar 7 in position along said slot. An angled plate 11 is 50 secured across the arms 2, and between said plate and the arm ends is placed a slideable plate 12 carrying a foot rest 13. This foot rest and its plate 12 is supported by rods 14 which work through the angled plate 11 and springs 15 coiled about the rods 14 and which bear at their lower ends on the plate

11 and have their upper ends in engagement with a suitable head carried by the rods, and which may be in the form of nuts and washers placed on the rods. An angled strap 16 is fixed to the front of the plate 12 and projects rearwardly over the upper edge of it, and engages the bow portion of the bar 7 when the arms 2 are in vertical position, as shown in Fig. 1.

60 Brackets 17 are secured to the arms adjacent the plate 11 and to said brackets are pivotally connected bars 18 which are also pivotally connected to opposite sides of the lower portion of the casting 3. As the table 70 swings into horizontal position these bars 18 draw the lower end of the casting 3 upwardly and forwardly.

A set screw 19 works through the vertical portion of the plate 11, when the arms are in upright position, and bears on the lower end 75 of the springs 6, limiting their forward movement.

The operation of the parts above described is as follows:—

80 When the device is assembled the screw 19 is adjusted so that the arms 2, are in upright position the lower ends of the spring 6 will be stopped or held in such position that the bolt 8 of the bar 7 will work readily 85 along the slotted casting 3 without engaging the notches, leaving it free movement the length of the slot. This adjusting screw need not be touched in future use of the table, unless to compensate for some slight 90 wear.

When the parts are in the position shown in Fig. 1, with step or foot rest 13 in highest position, and the casting 3 in approximately a vertical position, the bolt 8 will be 95 free to travel along the casting. If a child of fifty pounds weight is placed on the foot rest the plate 12 will move downwardly until the springs 15 will support such weight. The angled strap 16 will depress the bow portion of the bar 7, which works on the bolt 9 as a pivot, and the bolt 8 will travel up the slot of the casting opposite a particular notch 4. If now the arms are drawn down in a horizontal position to rest on the stand 1 bars 18 will swing with the arms and rock the casting causing bolt 8 to engage the notch opposite to which it has stopped. Then as the table is lowered the lower ends of spring 6 will be drawn rearwardly, the extent of such movement depending on the distance between the pivotal 100 105 110

point of the bar 18 with casting 3 and the notch engaged by bolt 8.

On the other hand if a man is placed on the foot rest whose weight will force the plate 12 to its lowest position the bolt 8 will travel to the upper end of the slot and engage the last, upper notch. Therefore when the table is swung into horizontal position the springs 6 will be drawn back to their maximum extent, due to the fact that the casting rocks under the pull of the bar 18 so that its upper end will be thrown rearwardly.

It will therefore be clear to those using such tables that the device described will cause the springs 6 to take such position that they will balance whatever weight, within practical limits, may be placed on the foot rest.

What I claim is:—

1. In a device of the kind described, a longitudinally slotted, pivoted casting having notches in the front edge of the slot, a tension spring, a bar pivotally connected to a free end of the spring and adapted to work loosely along the slot of the casting and to be brought into engagement with one of the notches, on rocking movement of the casting, a spring supported foot rest, downward movement of the foot rest rocking the bar on its pivotal point, and means for rocking the casting after the said foot rest has been depressed.

2. In a device of the kind described, a stand, a pivoted table, a notched pivoted casting, a tension spring for said table, a bar engaging said spring and casting and movable along the casting, a spring supported foot rest adapted to move the bar along the casting when the foot rest is depressed, and means connecting the casting to the table

thereby rocking said casting on lowering of the table, said bar engaging a notch of the casting when the latter is rocked.

3. In a device of the kind described, a stand, a table adapted to swing from an upright into a horizontal position, a counter-balancing spring for said table, a tensioning bar pivotally connected to the spring, a curved, longitudinally slotted casting having a series of notches, said tensioning bar being movable along the casting and adapted to interlock with said notches, a foot rest, spring supported, operatively connected with the tensioning bar, and bars pivotally connected to the lower end of the casting and to said table, as and for the purpose set forth.

4. In a device of the kind described, the combination with a stand and a pivoted table carried by the stand, of a slotted and notched casting arranged within the stand, a counter-balancing spring for the table, a U-shaped bar, transverse bolts therethrough, one of said bolts engaging the spring and forming a pivot for the bar, and the other working in the slot of the casting, a spring supported foot rest, means carried thereby engaging the U-shaped bar when the table is in upright position, and for rocking said bar on depression of the foot rest, thereby bringing the bolt into the casting slot opposite a notch determined by extent of downward movement of the foot rest, and means connecting the table and casting for bringing said bolt in engagement with said notch and rocking said casting on lowering of the table to horizontal position.

In testimony whereof I have affixed my signature.

WILLIAM E. RICE.
